UNITED STATES PATENT OFFICE.

WILSON E. PORTER, OF NEW HAVEN, CONNECTICUT.

PEDOMETER.

SPECIFICATION forming part of Letters Patent No. 738,482, dated September 8, 1903.

Application filed February 25, 1903. Serial No. 144,961. (No model.)

To all whom it may concern:

Be it known that I, WILSON E. PORTER, of the city and county of New Haven, State of Connecticut, have invented new and useful 5 Improvements in Pedometers, of which the following is a full, clear, and exact description, when taken in connection with the accompanying drawings, which form a part thereof, and in which—

10 Figure 1 represents a front elevation of a pedometer embodying my invention; Fig. 2, a rear view of the same with the case removed; Fig. 3, an edge view thereof; Fig. 4, a detail view of one of the movement-plates; Fig. 5, 15 a rear view of the spring-catch and cam-stop; Fig. 6, a detail view of the spring-catch alone, and Fig. 7 a detail view of one of the spring-pawls and part of the ratchet.

In all the figures similar letters of reference 20 represent like parts.

My invention relates to improvements in pedometers, and has for its object the production of a novel form in which the adjustment for the varied length of steps may be 25 easily and quickly accomplished.

To this and other ends my invention consists in the improvements and combinations of parts hereinafter described and claimed.

Referring to the drawings, the part designated by the letter A represents the case of 30 the pedometer, and B the dial thereof.

C and D are the two movement-plates supported by pillars c and carrying the operating mechanism, which consists of a lever F 35 and weight f, pivoted to a post G and held normally by a spring g against a stop H. A ratchet I is engaged by spring-pawls i and J, the former mounted on the movement-plate D and the latter on the lever F. Each of 40 these pawls is formed of a plurality of light metal springs i', i'', and i''' and j, j', and j'' of varying lengths. The difference between the length of the springs is so proportioned, as shown herein, that when the difference 45 is less than the distance from one tooth of the ratchet I to the next it is only necessary for the circumference of the ratchet to travel a part of the distance between two successive teeth for one of the springs to engage in one of the notches, as shown in the 50 enlarged detail view, Fig. 7. As the lever is moved from its normal position by the jar

caused by the step of the pedestrian, the spring-pawl J travels over the teeth of the ratchet I, which is held against movement by the pawl i. At the end of the stroke of the lever the spring g returns it to its normal position against the stop H, and the spring-pawl J rotates the ratchet I, which rotation is registered on the face of the dial by the hand 60 through registering mechanism of any usual character and not herein described. To adjust the stroke of the lever so that the ratchet I will be rotated the proper distance to register a single average step of the pedestrian, a cam-stop K is pivoted on the movement-plate D by a screw k or other suitable means. Said stops may be of substantially the form of that shown in the patent to Kuhn, No. 694,652, granted March 4, 1902. 70

The cam-stop K has rigidly connected to it a spring-catch L, which may be formed of sheet metal and curved to substantially the pattern shown in Figs. 5 and 6, whereby sufficient elasticity is obtained at the outer end of the 75 catch. Any movement of the spring-catch L will be communicated to the cam-stop K, and when the former is held stationary the latter will be likewise held. At its outer end the catch is provided with a stud l and a depending pin M. A portion of the periphery of the movement-plate D is formed on the arc of a circle having at its center the point N, at which the cam-stop K is pivoted, and its curved surface d is serrated for engagement 80 by the pin M on the spring-catch L. The surface of the movement-plate D in proximity to and corresponding with the curved surface d may be provided with a scale O to indicate the movement of the cam-stop K. 90

P is a knurled head on the end of the shaft carrying the indicator-hand b, by which the indicator may be adjusted as desired.

To adjust or regulate the length of movement of the weighted lever F, the pin M on the outer end of the spring-catch L is disengaged from the notch of the serrated edge d, (which disengagement is permissible because of the elasticity in the curved spring-catch,) and the spring-catch is moved in one direction or another and the cam-stop correspondingly turned on its pivot until the cam has been brought to a position to limit the stroke of the lever F as desired, when the pin M 100

will engage in the corresponding notch of the curved surface *d*.

I claim—

1. In a pedometer, the combination with a weighted lever; of an indicator; a registering-train for actuating said indicator, and operated by the movement of said weighted lever; a fixed stop to limit the movement of said lever in one direction; a rotatable cam-stop for limiting its movement in the reverse direction; and a spring-catch rigidly secured to said cam-stop for holding said cam in the desired position, substantially as described.

2. In a pedometer, the combination with a weighted lever; of an indicator; a registering-train for actuating said indicator and operated by the movement of said weighted lever; a fixed stop to limit the movement of said lever in one direction; a rotatable cam-stop for limiting its movement in the reverse direction; and a spring-catch rigidly secured to

1 said cam-stop to rotate the same and to hold it in the desired position, substantially as described.

3. In a pedometer, the combination with the movement-plate; of a weighted lever pivoted thereon; an indicator; a registering-train for actuating said indicator, and operated by the movement of said weighted lever; a fixed stop to limit the movement of said lever in 30 one direction; a rotatable cam-stop for limiting its movement in the reverse direction; a spring-catch rigidly secured to said cam-stop adapted to engage the serrated edge of said movement-plate, and to rotate said cam-stop, 35 substantially as described.

In witness whereof I have hereunto set my hand on the 24th day of February, 1903.

WILSON E. PORTER.
